UNITED STATES PATENT OFFICE.

NICHOLAS POWER, OF BROOKLYN, NEW YORK, ASSIGNOR TO NICHOLAS POWER COMPANY, OF NEW YORK, N. Y., A CORPORATION OF DELAWARE.

SAFETY DEVICE FOR MOVING-PICTURE MACHINES.

1,119,451.

Specification of Letters Patent.

Patented Dec. 1, 1914.

Application filed March 14, 1913. Serial No. 754,240.

To all whom it may concern:

Be it known that I, NICHOLAS POWER, a citizen of the United States, and resident of Brooklyn, in the county of Kings and State 5 of New York, have invented certain new and useful Improvements in Safety Devices for Moving-Picture Machines, of which the following is a specification.

This invention relates to improvements in 10 safety devices for moving picture machines and has for its object to provide a device which will absolutely prevent all possibility of fire reaching the film in the magazine in case the same should become ignited in its 15 passage through the machine. One device for this purpose which has given quite satisfactory results is disclosed in my prior Patent No. 959601, May 31, 1910, and designated in the trade by the term "magazine 20 valve." This mechanism comprises a chute through which the film enters the magazine with guide rollers at the entrance of the chute one of which has inclined slotted bearings so that the rollers lie closely against the 25 film to "wipe" off the flame of the burning film when it reaches the rollers. In practice this device has been modified to permit the machine to be more easily threaded by leaving a slot in the side of the chute so that 30 the film can be slipped edgewise into the device without unwinding the same to obtain a free end. This slit sometimes permits enough air to get to the film for it to burn through the "valve" particularly if 35 the fire has gotten a good headway before it reaches the rollers. My present invention is shown as an addition to the device disclosed in this patent and is designed to absolutely prevent passage of fire into the magazine, 40 but at the same time permits the film to be readily threaded in the machine. It is to be understood however that my present invention may be employed independently 45 of the magazine valve if desired and is quite effective for the purpose when so used. I have shown my improvements in the accompanying drawings in which,

Figure 1 is a side elevation partly in section of a portion of a moving picture machine equipped with my invention; Fig. 2 is an end view of the mechanism shown in Fig. 1. Figs. 3 and 4 are detail views on lines 3-3 and 4-4 of Fig. 1.

In the said drawings 1 represents the 50 magazine for receiving the film as it passes

through the projecting apparatus indicated generally by the numeral 2. The film is fed from a magazine 3 supported above the projecting apparatus by a suitably driven continuously rotating sprocket 4, from 55 which the film passes to the intermittently rotating sprocket 5 which successively feeds the pictures on the film into registration with the projection aperture of the machine. Beneath the projection aperture is 60 a continuously driven sprocket 6 which feeds the film into the magazine 1 where it is wound upon a reel driven through a slip gear to maintain a proper winding tension on the film. As constructed 65 without the attachment of the device forming the subject matter of this application, the upper wall of the magazine has attached to it the device shown in my prior patent which serves to guide the film 70 into the magazine. This device comprises briefly a metal frame 7 having upwardly projecting webs 8 and 9 separated a distance slightly greater than the width of the film 75 and carrying at their upper ends guide 80 rollers 10 one of which is mounted in inclined slotted bearings to bear against the surface of the film and hold the film in contact with the other roller during the movement of the film through the device. 85

At the outer side of the magazine valve the web 9 is formed in two pieces spaced slightly apart as indicated at 11 so that the film may be thrust edgewise between the rollers and it is because of the ventilation 90 permitted by this slit that the fire in some instances passes into the magazine without being put out. To correct this defect I provide the magazine valve with a supplementary chute or inclosing casing for the film 95 which extends from the same to the continuously rotating sprocket 6 which feeds the film into the magazine. This chute comprises a member 12 stamped out of sheet metal and provided with side flanges 13 to 100 engage the edges of the film to guide the same, and has the central portion 14 of its face offset from the edge portions to give it greater rigidity, and also to prevent contact of the same with the portion of the film which bears the picture. At its lower end the member 12 is curved to fit the frame of the magazine valve, and is fixedly attached thereto by suitable rivets or otherwise. The other member 15 of the chute may also be 105 110

stamped from sheet metal and is similar in shape to the member 12 except that its side flanges are spaced slightly farther apart to lie outside of the side flanges of the member 12 so that the edges of the flanges 13 engage the inner face of the member 15 to completely inclose the film and hold the members spaced apart sufficiently to permit free passage of the film. At its lower end the member 15 is hinged to the frame of the magazine valve on a suitable pivot rod 16 and its flange on the open side of the valve is widened as shown at 17 so as to closely cover the slit in the side of the valve when the member is in its operative position inclosing the film. A suitable spring 18 is coiled around the pivot rod 16 to hold the member 15 normally in its operative position and a latch 19 is provided for engaging a pin projecting from the member 15 to hold it in its open position to uncover the slit 11 and permit easy threading of the machine.

In the most modern form of moving picture machines the inner rear face of the machine is inclosed by a door 20. This door is preferably made out of sheet metal and is hinged on its edge 21 to the fixed portion of the machine casing. The rear face of the door is curved to conform to the outline of the machine and is provided at substantially its middle portion with a flat surface 24 having springs which engage the film adjacent the projection aperture to guide the same in its movement past the aperture. Unless this door is closed the machine cannot be operated as the film is not otherwise held in proper position for projection. To prevent the machine being operated unless the member 15 is adjusted to inclose the film I position the latch so that when the member 15 is held open it lies in the path of movement of the door 20 and hence the same cannot be closed and the machine operated. I may if desired provide the door with a trip to release the latch as it is closed, but it is sufficient for the purpose to prevent the door being closed until the fire shield 15 is properly adjusted.

The operation of the device will be clear from the above description. The fire shield not only incloses the film between the present magazine valve and the feed sprocket, but also covers the slit at the side of the valve when the shield is closed. The two members of the shield lie closely together and completely inclose the film and serve in effect to extinguish the flame by the chilling effect of the metal and also by cutting off the air from the burning film whereby it is choked with its own fumes.

Another important function of my device is its operation in connection with the winding mechanism for the film. In case the winding mechanism becomes inoperative

through failure of its driving connections or from other cause, the continued movement of the feed sprockets causes the film to pile up between the sprocket and the top of the magazine thereby damaging the film and increasing its liability to ignition. My improved fire shield closely embraces the film throughout its entire path from the sprocket to the magazine and the stiffness of the film as it is pushed forward by this sprocket is sufficient to cause the film to be thrust into the magazine where it will be protected against injury or ignition even if it is not wound upon the roll.

My present invention may be used to advantage in combination with the stop mechanism shown in my co-pending application No. 749,238, filed Feby. 18, 1913, by connecting the operating rod of the stop pawl to the member 15 to stop the machine when the member 15 is opened as, for instance, by the failure of the film to be thrust into the magazine should the winding device fail to work.

Having thus described my invention, what I claim and desire to secure by Letters Patent is:—

1. In a moving picture machine, the combination of film feeding and guiding means, a magazine for receiving said film therefrom, and a casing closely and completely inclosing said film adjacent said magazine said casing comprising a fixed member for engaging one face of said film, a hinged member for engaging the opposite face thereof, side flanges on one of said members overlying the edges of the other member, a spring for holding said members together and a latch for holding said hinged member in open position to permit said film to be threaded into said casing.

2. In a moving picture machine, the combination of a magazine for receiving the film, a feed sprocket for feeding said film to said magazine, an open-sided guide in the wall of said magazine for directing said film thereinto, and a casing for inclosing said film between said sprocket and said guide and provided with a portion adapted to close the open side of said guide.

3. In a moving picture machine, the combination of film feeding and guiding mechanism and a casing for inclosing said film throughout a portion of its path of movement, said casing comprising a movable side adjustable to open position for the reception of said film and to a closed position to completely inclose said film, and adapted when in open position to prevent operation of a portion of said feeding and guiding mechanism.

4. In a moving picture machine, the combination of a magazine for receiving the film, a feed sprocket for feeding said film to said magazine, and a casing completely

and closely inclosing said film throughout its entire movement from said sprocket to said magazine, and extending into sufficiently close proximity to said sprocket to receive the film fed thereby and to cause the same to be thrust by its own stiffness into the magazine by the feeding movement of the sprocket.

5. In a moving picture machine, the combination of a magazine for receiving the film, a feed sprocket for feeding said film to said magazine, film guiding members embracing a portion of said sprocket and extending from said feed sprocket to said magazine and closely engaging the opposite faces of said film, whereby said film will be thrust into said magazine by said feed sprocket.

6. In a moving picture machine, the combination of a film feeding mechanism, a magazine for receiving the film from said mechanism, a casing inclosing said film feeding mechanism, said casing having a door, a film guiding member for guiding the film in its passage from said feeding mechanism to said magazine, said guiding member be-

ing mounted for movement into and out of operative position in the path of movement of said door, whereby said door cannot be closed until said member is moved to its 30 operative position.

7. In a moving picture machine, the combination of a magazine for receiving the film, a feed sprocket for feeding said film to said magazine, and film guiding members 35 extending from said sprocket to said magazine, one of said members engaging a portion of the sprocket in such manner as to hold the edges of the film in engagement with the sprocket teeth, said guiding members closely engaging the opposite faces of the margins of the film whereby said film will be thrust into said magazine by the feeding movement of said sprocket.

Signed at New York, in the county of 45 New York and State of New York, this 11th day of March, A. D. 1913.

NICHOLAS POWER.
